PROCESS OF PRODUCING NATURAL
ANTIOXIDANTS

Loran O. Buxton, Maplewood, N. J., assignor to
National Oil Products Company, Harrison, N. J.,
a corporation of New Jersey

No Drawing. Original application February 20,
1942, Serial No. 431,700. Divided and this ap-
plication December 13, 1944, Serial No. 568,075

8 Claims. (Cl. 252—398)

This invention relates to the production of anti-
oxidants and to the stabilization of oxidizable
organic substances, primarily those of an oily
or fatty nature.

It is well known in the art that many oxidiz-
able organic substances, e. g., oils, fats and waxes
containing fatty acid radicals, as well as soaps
thereof, tend to be detrimentally affected by ex-
posure to atmospheric conditions for prolonged
periods of time. For example, many oils and fats
tend to develop considerable rancidity and under-
desirable tastes and odors upon prolonged exposure
to air. This instability of oils and fats tends to
be accentuated by conventional refining proc-
esses since in many cases the refining treatment
destroys or removes the natural antioxidants con-
tained in such substances. This characteristic
instability is particularly undesirable in connec-
tion with fat-soluble vitamin-containing oils
since these oils not only show the typical tendency
to become rancid upon exposure to air but also
tend to lose a considerable portion of their val-
uable vitamin activity. Other oxidizable organic
substances manifest their characteristic instabili-
ties in different fashions but in practically every
case their instability is highly undesirable.

As a result of the instability shown by many
oxidizable organic substances, many attempts
have been made to increase the resistance of
these substances to the action of oxidizing in-
fluences. For example, it has been proposed to
stabilize oils and fats by adding certain crude
vegetable oils thereto, the theory being that since
the crude vegetable oils suggested for use contain
natural antioxidants, these antioxidants would
serve to stabilize the oils and fats. This proposal
has, however, not met with any particular suc-
cess because of the fact that since the vegetable
oils do not contain very high percentages of the
antioxidants, disproportionately large amounts of
the oils have to be added to the substances to be
stabilized in order to achieve the desired anti-
oxidant effect. Several proposals have been ad-
vanced designed to recover valuable fractions
from vegetable oils but there has been no im-
portant success achieved along these lines with
regard to the production of effective antioxidants
therefrom. As a matter of fact, the art has gen-
erally believed that the vegetable meals, not the
oils expressed therefrom, were the most suitable
source of antioxidants and has turned away from
the idea of recovering antioxidants from such
oils.

It was been suggested that solvents, such as
ethyl alcohol, would be capable of extracting ef-

fective antioxidants from oil-free vegetable meals.
This proposal has several disadvantages. In the
first place, the antioxidants extracted from the
meals are generally not completely oil-soluble so
that in some cases it is not possible to form com-
pletely homogeneous mixtures of these anti-
oxidants with substances such as oils and fats.
In the second place, the antioxidants extracted
from vegetable meals may have extremely dark
10 colors and unpleasant odors and are generally
obtained in very poor yields. The result of these
disadvantages has been that the suggested meth-
od has not met with any substantial degree of
commercial success.

15 It has also been proposed to recover anti-
oxidants from vegetable oils by saponifying the
oils, separating the unsaponifiable portions by
successive extractions and fractionations. This
proposal has likewise been commercially unsuc-
cessful because it entails the destruction by
20 saponification of the valuable vegetable oils,
thereby rendering the process highly uneconomical,
and because the saponification destroys the
antioxidant properties of certain of the materials
25 contained in the oils; moreover, the necessity for
carrying out a number of extraction and frac-
tionation steps is clearly disadvantageous.

Because of the many disadvantages inherent in
prior processes for the production of antioxidants
30 there is still a considerable demand in the in-
dustry for a simple, economical and effective
method for preparing antioxidants which will
accomplish the desired results. Furthermore, be-
cause of the tremendous recent development in
35 the production and use of fat-soluble vitamin-
containing oils, the need for such antioxidants
has become particularly acute due to the well
known instability of vitamins contained in such
oils.

40 It is an object of this invention to provide a
simple and economical process for the produc-
tion of highly effective antioxidants.

45 A specific object of this invention is to provide
naturally occurring antioxidants capable of sta-
bilizing fat-soluble vitamin-containing oils.

Other objects of the invention will in part be
obvious and will in part appear hereinafter.

I have discovered that highly active antioxi-
dant compositions may be prepared from fatty
50 materials containing natural antioxidants by
treating such materials with highly polar sol-
vents which are substantially immiscible with the
fatty materials at room temperature or at tem-
peratures above room temperature. I have
55 found, contrary to all expectations, that although

the fatty materials themselves are immiscible with the polar solvents at room temperature or above, the natural antioxidants contained therein, or a substantial portion thereof, are soluble in the solvents. My discovery thus provides a simple, effective means of preparing highly potent natural antioxidant concentrates since merely by extracting a natural antioxidant-containing fatty material at about room temperature (i. e., about 10° C. to 30° C.) with a highly polar solvent immiscible therewith, the natural antioxidants contained in the fatty material become concentrated in the solvent. The fatty material and the solvent are readily separated, e. g., by decantation, centrifugation, etc., and the natural antioxidants easily recovered from the solvent, e. g., by vacuum distillation of the solvent, leaving as a residue a very active antioxidant fraction. My discovery is particularly applicable to the recovery of antioxidants from fatty oils such as vegetable and fish oils since the solvent extraction of such materials with highly polar solvents immiscible therewith yields products containing antioxidants in extremely active condition. I have further found that the extracts recovered from fatty materials may be blended with oxidizable organic substances to form mixtures extremely resistant to deteriorative oxidation. This invention is primarily concerned with the stabilization of oxidizable organic substances of an oily or fatty nature since my antioxidants may be easily blended with such substances to form completely homogeneous, stable mixtures.

A preferred embodiment of my invention involves the stabilization of fat-soluble vitamin-containing oils since the addition of my extracts to such oils not only prevents the development of undesirable rancidity and discoloration but also stabilizes the vitamin content of the oils so that there is relatively little destruction of either the vitamin A or vitamin D contained in the oils even after prolonged exposure to atmospheric conditions. My novel process has the additional advantage that the residual fatty materials from which the antioxidants have been extracted are more valuable than the fatty materials originally treated since a certain amount of refining takes place due to a substantial removal of color and odor along with constituents responsible for the production of "break." Thus my invention not only yields valuable antioxidants but also produces refined fatty materials suitable for a wide variety of purposes. The yields obtained in accordance with my process are excellent and the solvents employed are all readily available and comparatively inexpensive. As a result, this novel process for the preparation of antioxidants is extremely economical.

The fatty materials from which the antioxidants are extracted in accordance with this invention may be any fatty materials containing naturally occurring antioxidants, or mixtures of such fatty materials; preferably, crude oils containing such antioxidants are employed. The term "fatty material" is used throughout the specification and claims to include oils, fats and waxes containing fatty acid radicals. There are many such materials containing natural antioxidants known to the art. Thus, vegetable oils and fats such as soybean oil, wheat germ oil, corn germ oil, corn oil, oat oil, wheat bran oil, rye oil, olive oil, sesame oil, cottonseed oil, palm oil, cocoa butter, palm kernel oil, coconut oil, rice bran oil, rice germ oil, linseed oil, oliticia oil, tea-

seed oil, perilla oil, alfalfa seed oil, celery seed oil, flax seed oil, hemp seed oil, kapok oil, mustard seed oil, rape seed oil, poppy seed oil, sunflower seed oil, pumpkin seed oil, melon seed oil, peanut oil, and the like, may be treated. Another group of fatty materials which may be employed is the fish liver oils such as cod liver oil, tuna liver oil, halibut liver oil, shark liver oil, etc., as well as other marine oils such as menhaden oil, herring oil and sardine oil.

Other oils which may be treated in accordance with the present invention are tomato seed oil, grape seed oil, peach kernel oil, egg oil and whale oil. I prefer to produce my antioxidants from vegetable oils and in the detailed description hereinafter given particular reference will be made to the treatment of such oils; however, it is to be understood that other fatty materials may be used if desired.

The solvents which may be used in carrying out the process of the invention include methanol and ethanol, either of which may contain any suitable quantity of water or no water at all. Moreover, a mixture of these two solvents may be used. A solvent sold under the trade-mark "Solox" by U. S. Industrial Chemicals, Inc. was found to be quite efficacious in practicing this invention. The natural antioxidants which it is desired to extract from the fatty materials are soluble in methanol and ethanol at room temperature whereas the fatty materials themselves are immiscible therewith or relatively so.

In carrying out the extraction of the antioxidants from the oils with which they are associated, the oil to be treated is first mixed with the particular solvent to be employed. The relative proportion of oil to solvent may vary widely; the ratio of solvent to oil should be greater than one and, preferably two to fifty parts of solvent to one part of oil. If desired, the solvent-oil mass may be warmed to a temperature slightly or substantially above room temperature. By so doing, it is sometimes possible to obtain somewhat more intimate contact of the solvent with the fatty material and thereby obtain a more efficient and complete extraction of the natural antioxidants. The solvent solution and the fatty material may then be separated from each other at the elevated temperature or the mixture may first be allowed to cool to room temperature before completing this step of the process. The extraction is preferably carried out in an atmosphere of inert gas.

The antioxidant fraction extracted from the oil may be recovered in any suitable manner. As the solvent and the oil are immiscible at room or at temperatures substantially above room temperature, they may be separated by decantation, centrifugation or any other suitable means. The oil will generally be found to be somewhat lighter in color than originally and in many cases will have lost some of its original characteristic odor. Furthermore, in most cases it will be found that materials responsible for producing "break" have been removed from the oil by the extraction. Thus the oil which has been extracted by the process of this invention may be used for a wide variety of purposes in accordance with processes well known to the art.

The solvent solution may be filtered and then treated to remove the solvent therefrom, e. g., by vacuum distillation, whereby an extract is recovered containing relatively large amounts of highly active antioxidants. If desired, water may be added to the extract in order to precipitate some of the glycerides contained therein or some of the sterols may be removed; however, these steps

are not essential since the glycerides and sterols do not inhibit the antioxidant properties of the extract. If the extract contains an excessive amount of free fatty acids, these are preferably removed by treatment with alkali in a hydrocarbon or chlorinated hydrocarbon solvent medium or by other suitable methods. The extract ordinarily possesses the characteristic odor and color of the oil from which it is obtained and is generally slightly more viscous than the original oil. Tests carried out on vegetable oil extracts indicate that the iodine values of the extracts are substantially lower than those of the original oils. If a vitamin-containing fish liver oil is employed in the practice of the present invention, it will be found that the extract contains a considerable portion of the vitamins concentrated therein.

My novel antioxidants may be employed for the stabilization of all types of oxidizable organic substances, particularly those of a fatty nature, i. e., fatty oils, fats, waxes, soaps, vitamin concentrates, etc. Thus oils and fats of animal, vegetable or fish origin, such as cod liver oil, tuna liver oil, shark liver oil and other fish liver oils, as well as vitamin concentrates or vitamin-containing fractions obtained from such oils; corn oil, cotton seed oil, soybean oil and other vegetable oils; fats such as butter, margarine, lard, hydrogenated shortenings, palm oil, etc.; soaps of higher fatty acids and compositions containing such fatty materials as essential ingredients, e. g., cookies, cakes, crackers, breakfast cereals, etc., as well as food emulsions such as mayonnaise, may all be suitably stabilized in accordance with this invention. Furthermore, substances such as sulfonated oils and other sulfonated fatty compounds, amides, mono- and diglycerides and other fatty substances which tend to become rancid upon exposure to air, may be treated by this invention. Other materials subject to oxidative changes which may be protected with the products of this invention include cosmetics such as face creams, hand lotions, shaving creams, etc.; gasoline, mineral oil, lubricating oils, rubber, etc.

The amount of the extract added to the fatty material to be stabilized may vary considerably, depending upon the activity of the extract and the degree of instability of the fatty material. I have found that oils or fats containing anywhere from about 0.1% to about 20%, preferably from about 0.5% to about 5%, of my antioxidant extracts show striking improvements in their stability.

My antioxidants are particularly adapted for the stabilization of fat-soluble vitamin-containing oils or concentrates as well as vitamin-containing fractions recoverable from such products by vacuum distillation, solvent extraction or other processes. This is extremely fortunate for antioxidants capable of stabilizing such products have not as yet been made available on a wide scale. My antioxidants may be added to such materials in any suitable amount without imparting undesirable color, odor, taste or toxicity thereto. Furthermore, the incorporation of my antioxidants in such vitamin-containing products yields vitamin compositions of a stability such that they may be handled more easily and economically than compositions heretofore obtainable. These stabilized vitamin compositions may be employed in the same manner as ordinary vitamin compositions and thus may be incorporated in food materials of all types, emulsified to form valuable emulsions or put to other appropriate uses.

Substances of a fatty nature stabilized by the addition of my novel extracts thereto may be

heated to elevated temperatures without substantially affecting the activity of the antioxidants. Moreover, the heating of vitamin-containing oils stabilized by the addition of my extracts does not substantially reduce the vitamin activity of the oils. As a matter of fact, it was found that by adding the antioxidant extracts of the present invention to substances of a fatty nature having undesirable tastes and odors and subsequently heating the mixtures to elevated temperatures, e. g., 100° to 130° C., the undesirable tastes and odors of the substances were substantially minimized.

A further advantage of the fractions which are extracted from crude vegetable oil is that they have valuable emulsifying properties. For example, when a vitamin concentrate is mixed with the ethanol extract of one of the crude vegetable oils, the resulting solution can be readily dispersed in aqueous media to give stable dispersions and, because of the natural antioxidants contained in the extract, the vitamin potency in the alcohol solution is very stable. In dispersing vitamin concentrates in aqueous media for human consumption, it is preferred to use an ethanol solution of an antioxidant fraction and a vitamin concentrate. In some cases it may be desirable to extract the antioxidant fraction from the natural antioxidant-containing fatty material with some solvent other than ethanol. When this is done it is preferable to remove the solvent from the antioxidant fraction and then redissolve the fraction in ethanol before using the fraction to help disperse a vitamin concentrate in an aqueous medium.

A modification of the process hereinabove described which I have found to be particularly successful involves extracting a mixture of a fish liver oil and a vegetable oil containing natural antioxidants with one of the above solvents. As pointed out above, the extraction of a fish liver oil effects a concentration of the vitamins contained therein in the solvent. Furthermore, the antioxidants of the vegetable oil are also concentrated in the extract so that a highly potent, extremely stable extract is recovered. A similar extraction of a mixture of a vegetable oil and a fat-soluble vitamin concentrate yields an extremely stable extract constituted chiefly of the concentrate and the natural antioxidants and emulsifying agents of the vegetable oil. Furthermore, the vitamin concentrate which is recovered, particularly when the original concentrate was composed of the unsaponifiable fraction of a fish liver oil, is much improved in color, taste and odor over the original concentrate and also generally has a considerably higher potency than the original concentrate.

While the present invention is primarily concerned with the stabilization of oxidizable organic substances of a fatty nature, other oxidizable organic substances such as nonfatty substances containing vitamin C, pyrethrum, essential oils and other materials known to the art may be stabilized by treatment with my novel extracts.

The following examples are illustrative of the method of producing the extracts of this invention; amounts are given in parts by weight:

EXAMPLE I
70 200 parts of freshly prepared unrefined wheat germ oil were mixed with 800 parts of 100% methanol and the mixture warmed to about 50° C. in the presence of N₂ gas and then thoroughly agitated for 10 minutes. After allowing the mix-

ture to cool to room temperature, the clear supernatant solvent layer was decanted and the residual oil layer treated twice more exactly as before with fresh batches of methanol. The combined methanol extracts were then freed of solvent at a low temperature under reduced pressure and in the presence of N_2 gas. The resulting extract had an iodine value of 113 as compared to 124 for the original oil and exhibited very strong antioxidant properties.

EXAMPLE II

500 parts of virgin soybean oil were thoroughly agitated with 2000 parts of 100% methanol while maintaining in an atmosphere of N_2 gas. The mixture was then centrifuged to recover a clear solvent layer and a clear oil layer. The oil layer was then treated with another fresh batch of solvent exactly as before. The combined solvent extract fractions were freed of solvent under reduced pressure and in the presence of N_2 gas. The extract fraction had an iodine value of 116 as compared to 123 for the crude oil and possessed very strong antioxidant properties.

10 The residual oil layer after being freed of solvent was substantially free of "break" constituents.

EXAMPLE III

200 parts of crude corn oil were treated with 95% aqueous ethanol essentially as in Example I. The extract fraction, exhibited strong antioxidant properties. The iodine value was 109 as compared to 121 for the original oil.

EXAMPLE IV

100 parts of crude corn germ oil were treated with 97% aqueous methanol exactly as in Example I. The extract fraction was a very strong antioxidant.

In order to illustrate the improved stability displayed by vitamin-containing oils stabilized in accordance with the present invention, the following table is submitted. This table shows the relative stabilities of crude shark liver oil and shark liver oil refined to remove its odor, color and taste contrasted with the stability of the refined shark liver oil containing 5% of one of the extracts of this invention. These tests were conducted by maintaining the samples at a constant temperature of 34.5° C. in the presence of air for the indicated number of days and measuring the percentage of the vitamin A destroyed.

Table

Sample	Percent vitamin A destroyed in—		
	6 days	14 days	20 days
Crude shark liver oil	6.3	18.1	30.6
Refined shark liver oil	26.0	64.0	—
Refined shark liver oil containing 5% wheat germ oil extract prepared as in Example I	2.4	12.8	23.8
Refined shark liver oil containing 5% wheat germ oil extract prepared as in Example II	3.5	13.7	24.0
Refined shark liver oil containing 5% soybean oil extract prepared as in Example III	3.9	12.3	20.3
Refined shark liver oil containing 5% corn oil extract prepared as in Example IV	2.8	12.1	24.3

The above table clearly demonstrates the superiority of vitamin-containing oils stabilized by the addition of my novel antioxidants. It will be noted that the stabilized refined oils of this invention are even more stable than crude shark

liver oil so that it is evident that this invention permits the production of vitamin oils having no undesirable color, odor or taste and which are nevertheless exceedingly stable to oxidizing influences.

From the above description it will be evident that this invention provides a new and highly useful method for the recovery of naturally occurring antioxidants from fatty materials with which they are associated. This invention provides a process which is highly economical and which furnishes completely oil-soluble antioxidants. Furthermore, since the present process does not involve subjecting the fatty material being treated to saponification or any other chemical change, the residual material is particularly valuable for a wide variety of purposes after the removal of the antioxidants therefrom. Further, this invention provides a highly useful process for the stabilization of fat-soluble vitamin-containing oils and thus satisfies the demand of the industry for such products. The present process accomplishes the separation of antioxidants from materials which were thought to contain only a relatively small quantity of these antioxidants, thereby enhancing the value of the fatty materials by permitting the production of other valuable by-products therefrom. Because of these factors, it will be evident that this invention will be extremely useful to all those engaged in the production and stabilization of fatty materials. The word "crude" as used in association with the expressions "fatty material" and "vegetable oil" in the appended claims connotes the character and condition of these materials, i. e., that they are in their virgin and unrefined state.

This application is a division of application Serial No. 431,700, filed on February 20, 1942.

Since certain changes in carrying out the above process and certain modifications in the compositions which embody the invention may be made without departing from its scope, it is intended that all matter contained in the above description shall be interpreted as illustrative and not in a limiting sense.

Having described my invention, what I claim as new and desire to secure by Letters Patent is:

1. A process for obtaining antioxidants from fatty materials with which they are associated, which comprises contacting a crude fatty material containing natural antioxidants with a solvent selected from the group consisting of methanol and ethanol, separating a solution containing a highly active antioxidant extract from the remainder of the fatty material and recovering the antioxidant extract from the solvent solution thereof, said antioxidant extract having an iodine value lower than that of the original fatty material.

2. A process for obtaining antioxidants from vegetable oils with which they are associated, which comprises contacting a crude vegetable oil containing natural antioxidants with a solvent selected from the group consisting of methanol and ethanol, separating a solution containing a highly active antioxidant extract from the remainder of the vegetable oil and recovering the antioxidant extract from the solvent solution thereof, said antioxidant extract having an iodine value lower than that of the original vegetable oil.

3. A process for obtaining antioxidants from fatty materials with which they are associated,

which comprises contacting a crude fatty material containing natural antioxidants at a temperature substantially above room temperature with a solvent selected from the group consisting of methanol and ethanol, separating a solution containing a highly active antioxidant extract from the remainder of the fatty material and recovering the antioxidant extract from the solvent solution thereof, said antioxidant extract having an iodine value lower than that of the original fatty material. 10

4. A process for obtaining antioxidants from vegetable oils with which they are associated, which comprises contacting a crude vegetable oil containing natural antioxidants at a temperature 15 substantially above room temperature with a solvent selected from the group consisting of methanol and ethanol, separating a solution containing a highly active antioxidant extract from the remainder of the vegetable oil and recovering the 20 antioxidant extract from the solvent solution thereof, said antioxidant extract having an iodine value lower than that of the original vegetable oil.

5. A process for obtaining antioxidants from 25 vegetable oils with which they are associated, which comprises contacting a crude vegetable oil containing natural antioxidants with methanol, the ratio of methanol to oil being greater than one, and separating the methanol solution containing a highly active antioxidant extract from 30

the remainder of the oil, said extract having an iodine value lower than that of the original oil.

6. A process for obtaining antioxidants from vegetable oils with which they are associated, which comprises contacting a crude vegetable oil containing natural antioxidants with ethanol, the ratio of ethanol to oil being greater than one, and separating the ethanol solution containing a highly active antioxidant extract from the remainder of the oil, said extract having an iodine value lower than that of the original oil.

7. A process for obtaining antioxidants from vegetable oils with which they are associated, which comprises contacting a crude vegetable oil containing natural antioxidants with methanol, separating the methanol solution containing a highly active antioxidant extract and recovering the antioxidant extract from the methanol solution thereof, said extract having an iodine value lower than that of the original oil.

8. A process for obtaining antioxidants from vegetable oils with which they are associated, which comprises contacting a crude vegetable oil containing natural antioxidants with ethanol, separating the ethanol solution containing a highly active antioxidant extract and recovering the antioxidant extract from the ethanol solution thereof, said extract having an iodine value lower than that of the original oil.

LORAN O. BUXTON.
